UNITED STATES PATENT OFFICE.

CLARENCE C. CHRISMAN, OF ST. LOUIS, MISSOURI.

SHIFTING MECHANISM FOR TYPE-WRITERS.

No. 856,942.

Specification of Letters Patent.

Patented June 11, 1907.

Application filed October 28, 1906. Serial No. 340,214.

To all whom it may concern:

Be it known that I, CLARENCE C. CHRISMAN, a citizen of the United States, and a resident of St. Louis, Missouri, have invented 5 certain new and useful Improvements in Shifting Mechanism for Type-Writers, of which the following is a specification containing a full, clear, and exact description, reference being had to the accompanying 10 drawings, forming a part hereof.

My invention relates generally to type-writers, calculating machines, and the like, and more particularly to improved means of shifting so as to obtain impressions of the 15 upper and lower case characters.

In typewriters of the present construction, which make use of a single key-board, it has generally been the practice to provide a shift key and mechanism for shifting the carriage and roller carried thereby, and by my improved means this arrangement is dispensed with, and the lower ends of the type levers are moved slightly in order to accomplish the desired shift.

My improved arrangement permits each type bar to carry but a single character, instead of two characters, as is the present practice, which latter arrangement necessarily creates a certain amount of lateral strain 25 on the key bars when shifted from one position to another, and my improved arrangement also does away with considerable mechanism used in utilizing the shifting carriage and roller carried thereby.

To the above purposes, my invention consists in certain novel features of construction and arrangement of parts, which will be hereinafter more fully set forth, pointed out in the claims, and illustrated in the accompanying drawings, in which:-

Figure 1 is a vertical section taken through the center of a typewriter embodying my improvements; Fig. 2 is a horizontal section taken approximately on the line 2—2 of Fig. 45 1; Fig. 3 is an enlarged detail section taken on the line 3—3 of Fig. 2; Fig. 4 is a detail elevation of portions of one of the key levers and one of the type bar levers, and showing said key lever partially depressed; Fig. 5 is a 50 vertical section taken approximately on the line 5—5 of Fig. 3; Fig. 6 is an enlarged horizontal section taken on the line 6—6 of Fig. 5.

Referring by numerals to the accompanying drawings:-1 designates the typewriter frame, which is of the usual construction,

provided at the upper end with the usual ring 2, beneath which the key bars 3 are fulcrumed. Formed integral with the inner faces of the sides of the frame 1 and adjacent 60 the bottom thereof are the inwardly projecting flanges 4, and arranged to move backwardly and forwardly thereon are the ends of a pair of transverse bars 5, in which ends are formed slots 6, and through which slots pass 65 pins 7 which are seated in the flanges 4. The ends of this pair of bars 5 are connected by rods 8, or in any suitable manner; and formed through the transverse bars, at regular intervals apart, are apertures 9. Connected to 70 the rear one of the bars 5 are the forward ends of a pair of retractile coil springs 10, the rear ends thereof being secured to the rear of the typewriter frame 1.

11 designates the shifting key which is in 75 the form of a plate extending across the front of the key board of the typewriter, and integral with the ends of said plate are the rearwardly projecting arms 12 which are fulcrumed at their rear ends on pins 13 seated in 80 the sides of the typewriter frame; and integral with the rear ends of said arms 12 are the upwardly projecting arms 14, and rods 15 connect the upper ones of these arms with the front ones of the bars 5. The usual 85 spacing bar 11^a is arranged in front of the key board in the usual manner, and the supports or arms carrying said spacing bar pass through suitably formed apertures in the 90 shift key 11.

The bars 5 are normally positioned at the rear end of their limit of movement, and when the shift key 11 is depressed, said bars 5 are moved forwardly; and, when the shift key is disengaged, the retractile power of the 95 coil springs 10 return said bars 5 to their normal positions.

The key levers 16 are arranged in the lower portion of the typewriter frame in the usual manner, and normally lie in a horizontal 100 plane slightly above the bars 5, and with their rear ends journaled on a transverse shaft 17 in the rear of the machine. Formed in each one of these key levers is a short longitudinally extending slot 18, and leading upwardly from the center of each of said slots is a short vertical slot 19.

The key bars 3 are arranged in pairs, and one of each pair bears the upper case letter, and the opposite one the lower case letter; and 110 journaled in any suitable manner to the rear ends of each of the key bars are the upper ends

of the type bar levers 20 which are arranged in pairs to correspond with the pairs of key bars, and the lower ends of each pair of key levers are widened to form the parallel plates 21, and each corresponding pair of plates pass through one of the openings 9 in the transverse bars 5.

Journaled on pins 22 which are seated in the inner faces of each pair of plates 21 are rollers 23, which, when the plates are correctly positioned in the recesses 9, lie side by side, with one of said rollers occupying the rear end of the horizontal slot 18 in the corresponding type lever which passes between the pair of plates, and the adjacent roller which is carried by the opposite plate of each pair occupying the center of the horizontal slot, and immediately below the vertical slot 19.

20 The various parts of the apparatus are of such size and are so adjusted as that when the shift key 11 is depressed, the bars 5 are drawn forwardly a sufficient distance to bring the pairs of plates forwardly, which carries 25 the forward one of each pair of rollers into the forward end of the corresponding slot 18, and the rear one of each pair of rollers into the center of said slot, and immediately beneath the vertical slot 19.

30 Assuming that the type lever 20 carrying the roller which normally occupies the rear end of the slot 18 operates the type bar 3, which carries the lower case character, said lower case character will be moved upwardly 35 to strike against the under side of the roller whenever the corresponding key is depressed, owing to the position of the roller 23 carried by said lower case type lever in the slot 18, and, during this movement, the opposite 40 roller 23 carried by the type bar lever controlling the upper case character, remains stationary, as when the key lever 16 is depressed, the forward one of the rollers will not be affected, owing to its location in the 45 center of the slot 18, and immediately beneath the vertical slot 19 which receives said forward roller when the key bar is moved downwardly.

When it is desired to obtain an impression 50 of the upper case character on the roller, the shift key 11 is depressed, which pulls the transverse bars forwardly to their limit of movement, and simultaneously moves all of the plates 21 on the lower ends of the type bar levers forwardly, which action carries all 55 of the forward rollers 23 into the forward ends of the horizontal slots 18 and brings the rear rollers 23 to the centers of said slots and immediately beneath the slots 19. When the 60 proper key lever 16 is depressed, the roller in the forward end of the slot 18 will be moved downwardly, in turn carrying the corresponding plate 21 and key bar lever 20 downwardly and elevating the key bar carrying the upper 65 case character. During this movement, the

roller 23 on the lower case key lever 20 will not be affected, for the reason that it occupies a position at the center of the slot 18, and, therefore, enters the vertical slot 19 when the key lever is depressed. Thus, the operation of the shifting key 11 swings the lower ends of the type bar levers forwardly to change the positions of the rollers 23, and consequently brings the mechanism of the upper case character into position to be 70 operated when the key bar is depressed.

My improved arrangement does away with the shifting of the carriage and roller on top of the machine, and can be applied to all forms of computing and like machines 75 wherein type levers and type bars are made use of.

I claim:—

1. In a writing machine, a series of type bar levers, a key lever for said series, and a 85 pin and slot connection between said series of type bar levers, and the key levers, whereby any one of the series of type bar levers may be actuated by the key lever, in combination with a shifting mechanism; substantially as 90 specified.

2. In a writing machine, a series of type bar levers, key levers for said series, a pin and slot connection between the type bar levers and the key levers, a shifting mechanism whereby one set of type bar levers may be moved from its normal position, disengaging its connection with the key levers, which movement causes a disengaged set of type bar levers to become engaged with the key 95 levers; substantially as specified.

3. The combination with a writing machine, provided with the usual type bars, of type bar levers pivotally connected to the type bars and arranged in pairs, key levers 105 adjacent the pairs of type bar levers, and a shifting mechanism whereby the set of type bar levers normally engaged with the key levers may be moved horizontally to disengage the entire set normally engaged, and engage and bring into action a set which, previous to the movement, was disengaged; substantially as specified.

4. The combination with a writing machine, provided with the usual type bars, of 115 type bar levers pivotally connected to the type bars, depending therefrom, and arranged in pairs, a key lever passing between the lower ends of each pair of type bar levers, a connection between the type bar levers and the key levers whereby either one of the type bar levers may be actuated when the key lever is depressed, and means whereby the lower ends of each pair of type bar levers are shifted horizontally; substantially 120 as specified.

5. The combination with a writing machine provided with the usual type bars, of type bar levers pivotally connected to the type bars, a connection at the junction of 125

said type bar levers and the key levers whereby the set of type bar levers normally engaged may be disengaged from the key levers, which movement throws said set of type bar levers out of action and engages and brings into action another set of type bar levers; substantially as specified.

6. The combination with a writing machine, provided with the usual type bars, of type bar levers pivotally connected to the type bars, depending therefrom, and arranged in pairs, a key lever passing between the lower ends of each pair of type bar levers, a pin and slot connection between the type bar levers and the key levers whereby either one of the type bar levers may be actuated when the type lever is depressed, and means whereby the lower ends of the type bar levers are shifted horizontally to change the position of the pins in the slots of the connection between said type bar levers and the key levers; substantially as specified.

7. The combination with a writing machine, provided with the usual type bars, of type bar levers pivotally connected to the type bars, depending therefrom, and arranged in pairs, anti-friction rollers arranged

on the adjacent faces of the lower ends of each pair of type bar levers, a key lever passing through each pair of type bar levers, and there being a slot formed in each key lever to receive the anti-friction rollers; substantially as specified.

8. The combination with a writing machine, provided with the usual type bars, of type bar levers pivotally connected to the type bars, depending therefrom, and arranged in pairs, anti-friction rollers arranged on the adjacent faces of the lower ends of each pair of type bar levers, there being a slot formed in each type bar lever to receive the anti-friction rollers, and means whereby the lower ends of the type bar levers are shifted horizontally to change the positions of the rollers in the slots of the key levers; substantially as specified.

In testimony whereof, I have signed my name to this specification, in presence of two subscribing witnesses.

CLARENCE C. CHRISMAN.
